ELECTRICALLY NOISELESS PROGRESSIVE
CONTACT MEANSRaymond P. Mork, Cincinnati, Ohio, assignor to
The Baldwin Company, Cincinnati, Ohio, a corporation of Ohio

Application July 3, 1948, Serial No. 36,886

13 Claims. (Cl. 201—62)

1

My invention relates to progressive electric contact means such as may be employed with an electric resistance element to provide either a continuously variable resistor or a potentiometer.

The primary object of my invention is to provide a durable, economical and electrically noiseless progressive contact means.

Another object of my invention is to provide an electrically noiseless, continuously variable resistance device or potentiometer which is particularly adaptable to circuits carrying small electric currents such as occur in electronic devices, radio receivers, electric musical instruments, electric measuring equipment and the like.

A further object of my invention is to provide variable resistance means in which minor irregularities in the surface of a resistance element and/or the presence of foreign particles on a resistance element do not result in abrupt resistance changes, and hence noise in circuits which feed amplifiers and loud speakers.

A specific object of my invention is the provision of simple, inexpensive, dependable and durable apparatus suitable for use as a pedal actuated volume control for electrical musical instruments.

These and other objects of my invention which will be set forth hereinafter, or will be apparent to one skilled in the art from the following teachings, I attain by that construction and arrangement of parts and in that mode of operation of which I shall now describe an exemplary embodiment. Reference is made to the accompanying drawings wherein:

Figure 1 is a plan view of a resistance element disposed upon the base of a variable resistance device in accordance with my invention.

Figure 2 is a plan view of a contact strip employed in my invention.

Figure 3 shows the underside of the contact strip of Figure 2.

Figure 4 illustrates a plan view of a potentiometer, as an embodiment of my invention, employing the elements of Figure 1 and Figure 2.

Figure 5 is an elevational view of the structure of Figure 4.

Figure 6 is an enlarged sectional view 6—6 of Figure 5.

Figure 7 is a portion of a variable resistor according to my invention.

Figure 8 is a plan view of a volume control apparatus with part of the cover broken away.

Figure 9 is a side elevation thereof.

Figure 10 is a plan view from the reverse side.

Figure 11 is a partial longitudinal sectional

2

view taken along the section line 11—11 of Figure 10.

Figure 12 is a transverse sectional view taken along the section line 12—12 of Figure 11.

5 Figure 13 is a perspective view of a bearing block.

Figure 14 is a view, partly in elevation and partly in section showing the volume control device in use as a pedal-actuated swell control 10 in an electrical musical instrument.

Briefly, according to my invention, I employ elastically deformable, electrically conductive material interposed between a resistance element and a contactor, which material is caused to contact the electrical resistance element progressively and without tangential relative motion at the area of contact. In so doing, I not only eliminate friction between the contact surfaces, thus minimizing wear, but also I provide a contact surface

15 which by virtue of its own deformability makes intimate contact with the resistance element in spite of minor irregularities in the resistance element or the contactor and/or in spite of the presence of foreign particles thereon, both of 20 which conditions, when present in known practical devices of this general type, may cause abrupt changes in the electrical resistance offered by such devices when a resistance variation is effected. Such abrupt changes are often referred to as "electrical noise," because of the crackling sound produced when such devices are employed 25 to vary currents in electroacoustic systems.

I shall now describe a progressive electrical contact means in accordance with my invention 30 and capable of general use, after which I shall show it in use as a volume control for an electrical musical instrument.

In Figure 1 an area 1 of an insulative base 2 of a phenolic or other suitable material may be 35 coated with a layer of a carbonaceous or other material having a desired resistivity. Areas 3 and 3a, preferably of a conductive lacquer or a thin metallic layer partially underlying the ends of the coating 1, provide means for making electrical connections thereto, as described below.

In Figure 2, a flexible contact assembly indicated generally at 4, comprises a flexible, resilient metallic strip 5, preferably of phosphor bronze, which will normally be maintained above the 40 resistive layer in a position to be depressed into contact with it at various points throughout its length.

Between these elements I interpose a resilient, elastic, compressible material as indicated above.

50 This is most conveniently done by cementing

upon the underside of the contact strip 5 by means of a conductive rubber cement, i. e. a rubber cement containing dispersed finely divided conductive material, a strip 6 of an elastically deformable, electrically conductive material such as a commercially available natural or synthetic rubber, elastic resin or the like (hereinafter referred to as an elastomer) having finely divided particles of carbon incorporated therein. The latter strip is indicated at 6 in Figure 3, which shows the underside of the assembly 4 of Figure 2. Other modes of assembly are practicable, such as vulcanizing a thin layer of the rubber substance to a sheet of phosphor bronze and cutting the sheet into strips. It is within the scope of my invention to employ a strip of cloth or other mesh fabric impregnated and coated with the conductive elastomer.

The elements of Figures 1 and 2 may be assembled into a potentiometer such as that shown in Figures 4 and 5, wherein the elements bear the same indicia as in the preceding figures. The contact member 4 may be fastened by means of a screw 7 to the base 2, being spaced slightly therefrom by a washer 8. A spaced relationship between the contact member 4 and the resistive coating 1 may be maintained by a tension spring 9, one end thereof engaging a slot 10 in the member 4 and the other end engaging a riveted post 11. A similar post 12 projects from the base 2 through the slot 10 in the contact means 4 and acts as a guide to prevent transverse motion thereof. Screws 13 and 13a, and associated nuts provide means, in contact with the areas 3 and 3a, for making electrical connections to the resistive element 1.

An actuating member 14 of any suitable rigid material, preferably carbon, may be connected to any suitable mechanical system providing both a longitudinal motion for the actuator 14 and sufficient downward force to bring an area of the strip 6 into contact with the resistive coating 1. The longitudinal movement provides for variation of resistance in the device as will be clear. I may also employ a rolling actuator in the place of the sliding one described above. Such a roller is illustrated at 16 in Figure 7. Figure 6 is an enlarged sectional view 6—6 of Figure 5 showing approximate relative sizes of the various elements described above.

The illustrated structure is one in which there is a minimum of sliding motion between the strip 5 and the resistive coating 1, making for long life of these elements. The interposition of the resilient, deformable electrically conductive substance between the strip 5 and resistive coating 1 has the effect of minimizing wear still further, but more importantly it has the effect of conforming by slight deformation, to the surface irregularities of the resistive coating, and of contacting that surface in spite of slight amounts of foreign materials thereon, so that good, positive electrical contact is made at all times, and so that, as the position of contact is varied by movement of the actuator 14, abrupt, sporadic changes in resistance will not occur. Thus, electrical noise is eliminated. The effect occurs irrespective of the area of contact as determined by the shape of the actuator 14. Since the irregularities in the surface of the resistive coating 1 are minute, no great deformability is required in the layer 6. Hence, this layer can be very thin, say of the order of 5 to 15 thousandths of an inch, although this is not a limitation. Changes in the specific resistivity of the layer 6, if they occur, are

not of importance except as explained below, since the current is required to flow only through the thinnest section of the layer 6.

It will be obvious to those skilled in the art that the illustrated embodiment of my invention may be employed either as a variable resistor, in which case connections can be either between the screws 7 and 13 or 7 and 13a, or as a potentiometer, in which case connections can be made to screws 7, 13 and 13a in the manner usually followed in this art. However, if I wish to provide a structure for use only as a variable resistor, I prefer to eliminate the screw 13 near the left-hand end of the structure of Figures 4 and 5, employing a terminal screw 15, as shown in Figure 7, to connect the contact means 4 to the left-hand end of the resistive element 1 on the base 2. The right-hand end, not shown, of the structure of Figure 7, may be similar to that of Figures 4 and 5. Connections for obtaining a variable resistance may be made to the terminal screws 15 and 13a. Also in Figure 7, I have shown a rigid roller 16 which I may employ, if I so desire, in the place of the actuator 14. By increasing the diameter of the roller 16, I may vary, as desired, the area of contact between the layer 6 and the resistive element 1. However, if I wish to obtain a relatively large area of contact with a relatively small diameter roller, I may employ a roller of a soft rubber-like material, applying a sufficient force between the roller 16 and the resistive element 1 to flatten the periphery of the roller at its area of contact with the strip 5, thus causing a larger area of the layer 6 to contact the resistive element 1.

In Figures 8 to 11, I have shown an embodiment of my invention suitable for use as a pedal actuated volume control in an electrical musical instrument. In this embodiment, I provide a channel shaped metal body 17 having flanges 17a at the ends of the legs of the channel. The channel is provided with a removable cover 19 which may be held in place by screws 18 or the like engaging the flanges 17a.

The base of the channel is provided with openings such as 20, 21, and 22 in Figure 10 through which the means for making electrical contact with the potentiometer are accessible. Thus at 23 and 23a, I have indicated contact lugs to which soldered connections may be made which lugs may be used in connection with or in place of terminal screws 13 and 13a in Figure 4. The base of the channel may also be provided with other openings such as 24 to permit the base plate 2 to lie snugly against the base of the channel in spite of projections on the bottom side of the base plate, such as the rigid ends of the posts 11 and 12. I prefer, however, to line my channel with a thin layer of flexible insulative sheet material 25, which also serves in cooperation with other parts to provide a dust-tight construction.

The cover plate 19 may also be lined with a layer preferably of felt 26 or other suitable porous material which may be impregnated with a suitable lubricant.

The ends of the channel are closed by means of blocks 27, preferably though not necessarily of wood with the grain in the direction of the arrow in Figure 13. These blocks may be impregnated with a suitable lubricant such as graphite dispersed in an oily vehicle. The top surface of each block is provided with a groove 28 to accept a sliding bar 29 which carries the actuator for the potentiometer. The blocks are

held in place at the ends of the channel by screws or the like 30, with a suitable clearance for the passage of the bar 29. At the bottom, to permit expansion of the wood blocks and to contribute to dust-tightness, I may provide a layer of felt 31 or other suitable resilient substance.

The sliding bar 29, which may if desired be provided with rivets or other abutment members 32 to limit its motion within the channel, lies in the grooves 28 of the blocks 27 and beneath the cover element 19. An extending end of the bar is perforated as at 33 or otherwise provided with means whereby it may be connected with actuating mechanism. Within the channel, I provide a spring element 34, one end of which is attached to the bar 29 and the other end of which bears an actuating element which will bear against the phosphor bronze strip 5. As shown in Figure 11, an exemplary construction comprises a block 35 of insulative material which carries a rounded carbon element 14a to slide along the strip. Other constructions may be employed. The spring 34 presses the actuator element 14a into contact with the strip 5 with sufficient pressure to deflect the layer 6 against the resistive coating 1.

For mounting the structure of Figures 8 to 12 in an electrical musical instrument, I prefer to provide a spring leaf member 36 which at one end is riveted or otherwise fastened against a side leg of the channel shaped body 17. At the other end, it is provided with one or more perforations 37, whereby it may be screwed or bolted against a suitable support such as the base member 38 of a musical instrument, as shown in Figure 14. Here the base member is provided with a mounting block 39 to which a pedal 40 is pivoted as at 41. The bar 29 of the potentiometer device is pivoted to a bracket 42 on the underside of the pedal 40. As is known in the art, the pivoting elements for the pedal are preferably so constructed as to provide stops limiting the motion of the pedal. The spring 36 not only mounts my potentiometer in position as shown, but permits the potentiometer structure to swing in order to accommodate the rocking motion of the pedal. Connections are made to the potentiometer by means of a flexible cable or leads indicated generally at 43.

The operation is steady, devoid of lost motion, smooth in action, and noiseless. It is inherently lubricated and essentially dust-proof.

Regarding the electrical properties of the various elements described herein as an exemplary volume control, a practical device I have constructed employs a coating 1 having a resistance of approximately 500 ohms between the terminal screws 13 and 13a. The electrically conductive strip 6, is of a commercially available conductive rubber having a thickness of approximately .015 inch and an electrical resistivity of approximately 2 ohm-centimeters. The strip 5 is of .005 inch phosphor bronze, with a rigid graphite actuator 14. I may prefer in the case of a relatively low resistance control, such as the one just described, to cover the elastically deformable strip 6, and for the resistive coating 1, with a thin coating of colloidal carbon applied in suspension in a liquid vehicle which subsequently evaporates. Such a coating has been found beneficial due to the fact that after prolonged use, the strip 6 increases in surface resistivity. This thin coating helps to

stabilize the resistivity of the layer 6 at a desired low value.

In the case, however, of a structure employing a coating 1 having a relatively high resistance between terminals—say 10,000 ohms, such a surface coating is not so necessary for the deformable strip 6. If a material having inherently stable resistivity in spite of prolonged use can be found, a low resistivity surface coating can probably be dispensed with entirely.

In its broader aspects, my invention is not limited to the embodiment herein disclosed. For instance it is within the scope of my invention to employ a circularly disposed resistance element, a similarly shaped contact element, and a rotating actuating means for progressively shifting the area 7 contact between a conductive elastomer and a resistance element.

Modifications may be made in my invention without departing from the spirit of it. Having thus described my invention in an exemplary embodiment, what I claim as new and desire to secure by Letters Patent is:

1. A variable resistance device comprising in combination a resistance element, a contact unit comprising a resilient, flexible metallic strip having an elastically deformable, electrically conductive layer disposed upon a surface thereof adjacent said element, and means operative upon said member for forcing successive portions of said layer into contact with said element.

2. The combination claimed in claim 1, in which said resistance element comprises a layer of resistive material disposed upon an insulative base member having terminals mounted thereon for making connections to said resistance element and to said contact unit.

3. A variable resistance device comprising in combination an elongated insulative base having a resistive coating disposed longitudinally thereupon, terminal means connected to the ends of said coating, a contact unit having an end affixed to said base, terminal means for said end, said unit comprising a flexible, resilient metallic strip having an elastically deformable, electrically conductive layer disposed thereon, means in connection with the other end of said contact unit normally maintaining at least a portion of said layer in a spaced relationship with respect to said resistive coating, and means operative upon said strip for forcing successive portions of said layer into contact with said coating.

4. A potentiometer device comprising in combination an elongated insulative base having a resistance coating disposed longitudinally thereon, terminal means electrically connected to the ends of said coating, a contact unit having an end spacedly affixed to said base, terminal means for said end, said unit comprising a flexible, resilient, metallic strip having an elastically deformable, electrically conductive layer disposed thereon, means in connection with the other end of said contact unit tending to maintain said layer in a spaced relationship with respect to said resistive coating, and means operative upon said strip for forcing successive portions of said layer into contact with said coating.

5. In a variable resistance device, a base having an elongated rigid resistive element thereon, a resilient, flexible metallic member normally lying above said element, but compressible into contact therewith at various points throughout its length, and, interposed between said member and element, a resilient, flexible, deformable, electrically conductive substance acting, when said

member and element are pressed together, to increase the area of effective electrical contact therebetween.

6. In a device of the character described, a channel-shaped body, a cover therefor, grooved blocks closing the ends of the channel-shaped body, a bar slidable in the grooves of said blocks and beneath said cover, a progressive contact device within said channel-shaped body, and a resilient actuator for said progressive contact device affixed to said bar within said channel-shaped body.

7. The structure claimed in claim 6 wherein said cover is faced within with a lubricant-impregnated porous material serving as a bearing surface for said bar.

8. The structure claimed in claim 6 wherein said cover is faced within with a lubricant-impregnated porous material serving as a bearing surface for said bar, and wherein said blocks are blocks of wood impregnated with lubricant.

9. The structure claimed in claim 6 wherein said cover is faced within with a lubricant-impregnated porous material serving as a bearing surface for said bar, and wherein said blocks are blocks of wood impregnated with lubricant, and wherein said channel-shaped body is perforated to permit electrical connections to said progressive contact device, and is lined within with a flexible insulative sheet material coating with the other recited elements to provide a substantially dustproof construction.

10. The structure claimed in claim 6 wherein said cover is faced within with a lubricant-impregnated porous material serving as a bearing surface for said bar, and wherein said blocks are blocks of wood impregnated with lubricant, and wherein said channel-shaped body is perforated to permit electrical connections to said progressive contact device, and is lined within with a flexible insulative sheet material coating with the other recited elements to provide a substantially dustproof construction, and wherein a projecting end of said bar at one end of said body is adapted for connection to a rocking actuator, the other end of said body having a projecting spring leaf attached thereto, and adapted to be affixed to an external support thereto,

whereby said device may be mounted to rock to accommodate the rocking motion of said actuator.

11. The structure claimed in claim 10 in which said progressive contact device comprises an insulative base affixed to said body and having a resistive coating thereon, a metallic strip supported above said resistive coating and depressible into contact therewith by said actuator, and a coating of elastic, deformable, resilient electrically conductive substance on the surface of said metallic strip facing said resistive coating.

12. The structure claimed in claim 6 in which said progressive contact device comprises an insulative base affixed to said body and having a resistive coating thereon, a metallic strip supported above said resistive coating and depressible into contact therewith by said actuator and a coating of elastic, deformable, resilient, electrically conductive substance on the surface of said metallic strip facing said resistive coating.

13. The structure claimed in claim 6, including a rocking actuator, said bar being pivotally connected thereto at a point having arcuate motion, and a leaf spring projecting from said device and fixed to an external support, whereby to accommodate the rocking motion of said actuator.
